(57) **CLAIM**

The ornamental design for a display screen with active reservation graphical user interface, as shown and described.

DESCRIPTION

The sole FIGURE is a front view of an image of a display screen with a an active reservation graphical user interface for active reservation.

The outermost broken line in the FIGURE illustrates a display screen, and forms no part of the claimed design. The remaining broken lines, including all text and icons, illustrate portions of the graphical user interface that form no part of the claimed design.

1 Claim, 1 Drawing Sheet
